D. J. POWERS AND HENRY B. STEVENS, OF MADISON, WISCONSIN, ASSIGNEES TO
D. J. POWERS, ASSIGNEE TO BUFFALO AGRICULTURAL-MACHINE WORKS.

Letters Patent No. 96,264, dated October 26, 1869.

IMPROVED SUGAR AND SORGHUM-MILL.

The Schedule referred to in these Letters Patent and making part of the same

To all whom it may concern:

Be it known that we, D. J. POWERS and HENRY B. STEVENS, of Madison, in the county of Dane, and State of Wisconsin, have invented an Improved Mill, for Crushing and Expressing the Juice from Sorghum and Sugar-Cane Stalks; and we do hereby declare that the following is a full and exact description thereof, reference being had to the accompanying drawings, making part of this specification—

Figure 1 being a plan of the mill;

Figure 2, a side elevation thereof, together with the carrier which conveys the pressed stalks from the mill;

Figure 3, a side view of the cast-iron bed of the mill;

Figure 4, a top view of the same; and

Figure 5, a transverse section of the three pressure-rollers in their relative positions, as mounted in the mill.

Like letters designate corresponding parts in all of the figures.

We cast the bed A, on which the working-parts are to be mounted, in one piece, of such a shape as to furnish fixed oblique bearings n n, for the two lower pressure-rollers, and to form a receptacle, w, to hold the juice as it is expressed by the rollers, and from which to draw at convenience. This construction suberves economy, compactness, strength, and convenience.

The driving-shaft of the mill also may have its bearings in the bed, below its receptacle w, or it may pass entirely under the bed.

This driving-shaft B extends through or under the bed, so that it may gear, at one side of the mill, with one of the lower pressure-rollers, and at the other side of the mill, with the other of these pressure-rollers.

Thus, at one side, a pinion, F, on the driving-shaft, gears into a cog-wheel, G, on the shaft d of the pressure-roller D, and at the other side, a pinion, H, on the driving-shaft B, gears into a cog-wheel, I, on the shaft f of the pressure-roller E.

Two purposes are gained by this method of gearing:

First, by thus driving the two pressure-rollers, each by a separate pinion, on the driving-shaft, the strain is divided between the two pinions, and they therefore do not wear out so fast, and are much less liable to break.

Second, it enables us to locate the two lower pressure-rollers close together, (as near as may be without their touching each other,) whereby we avoid the liability of the stalks passing down between these rollers, instead of taking their proper course between the lower pressure-rollers and the upper pressure-roller C.

When a single pinion is employed to drive both of

the lower pressure-rollers, there is necessarily a considerable space between these rollers, so that their cog-wheels shall not come in contact with each other, and thus there is a great liability of the stalks going down between these rollers. This trouble is obviated by our arrangement.

The upper roller C is driven by the cog-wheel G on the shaft of one of the lower rollers, gearing into a pinion, J, fig. 2, on its shaft j; and, if desired, there may be a similar pinion on the other end of its shaft, receiving power from the cog-wheel I of the other lower roller.

The bearings k k, in which the journals of the upper roller turn, fit loosely in their seats M M, so that the roller can have sufficient play to adapt itself to the lower rollers, according to the pressure exerted by either, and equalize their action.

The strap-bolts L L passing over these bearings, and having the India-rubber blocks or washers l l at their lower ends, allow this free movement of the upper roller at the same time that strong pressure is exerted.

The nuts m m adjust the amount of pressure and space between the rollers.

The endless-belt carrier N is mounted in a frame, p p, which is hinged, by the lower shaft of the belt, in standards of the main frame of the mill.

There is a pinion, o, on this shaft, into which an intermediate pinion, n, gears, as well as into one of the roller cog-wheels, as G, and receives and transmits the motion to the carrier.

This positive gearing from the mill, and applied to the carrier, at the common centre of its attachment to the frame of the mill, and on which the carrier-frame turns, is an excellent arrangement, simple, effective, and not liable to any disarrangement.

It is also as compact as possible; and, what is of essential importance, the lower end of the endless belt is brought into close proximity to the rear lower roller D, and in such relative position thereto as properly and without fail to receive the bagasse as it comes from the rollers.

We employ an improved arrangement for tightening the endless belt and proportioning the tension to the weight of the stalks conveyed. It is by means of a shoe, P, in which the upper roller s of the endless belt is mounted, and which has a sliding movement in slots r r of the frame p.

Then the supporting-legs q q are pivoted to this shoe, and when the carrier is supported thereby, as indicated in fig. 2, the weight of the carrier, pressing on the legs, slides the shoe P upward till the belt N is tightened. This arrangement is entirely self-acting, and is very simple, convenient, and effective.

What we claim as our invention, and desire to secure by Letters Patent, is—

1. The combination and arrangement of the driving-shaft B, and the pinions F and H thereon, with the lower rollers D E, and their respective pinions G and I, so that the shaft extends underneath, the length of the rollers, and its pinions F and H gear respectively into the pinions G and I, at opposite ends of the rollers, thereby to enable the rollers to be located close together, for the purpose herein specified.

2. In combination with the above, the arrangement of the bagasse-carrier, so that its belt is driven by the pinion G, of the rear lower roller G, by means of two pinions *n* and *o*, around the shaft of which latter the carrier turns for adjustment, thereby bringing the

belt in close proximity and proper relation to the said roller, as herein set forth.

3. The sliding shoe P, of the carrier, arranged and operating substantially as and for the purpose herein specified.

The above specification of our improved mill for crushing and expressing the juice from sorghum and sugar-cane stalks, signed by us, this 21st day of February, 1866.

D. J. POWERS.
